US00D939206S

(12) **United States Design Patent** (10) **Patent No.:** **US D939,206 S**
(45) **Date of Patent:** **** Dec. 28, 2021**

(54) **BACKPACK**

(71) Applicant: **YETI Coolers, LLC**, Austin, TX (US)

(72) Inventors: **Alex Baires**, Austin, TX (US); **Derek G. Sullivan**, Austin, TX (US); **Erik Steven Larson**, Austin, TX (US); **Vivian Lai**, Austin, TX (US); **John Loudenslager**, Austin, TX (US)

(73) Assignee: **YETI Coolers, LLC**, Austin, TX (US)

(**) Term: **15 Years**

(21) Appl. No.: **29/646,104**

(22) Filed: **May 1, 2018**

(51) LOC (13) Cl. **03-01**

(52) U.S. Cl.

USPC **D3/217**

(58) **Field of Classification Search**

USPC D3/215-217, 273, 289, 290, 318, 321,

(57) **CLAIM**

The ornamental design for a backpack, as shown and described.

DESCRIPTION

FIG. 1 is a top, front, right perspective view of a backpack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, right perspective view of a backpack showing our new design in an open configuration; and,

FIG. 9 is a top, front, right perspective view of a backpack showing our new design in an open configuration.

The broken lines within the shaded areas represent unclaimed stitching. The remaining broken lines depict portions of the backpack that form no part of the claimed design.

1 Claim, 9 Drawing Sheets
